UNITED STATES PATENT OFFICE.

AMOS A. GROSE, OF MADISON TOWNSHIP, ST. JOSEPH COUNTY, INDIANA.

RAILWAY-RAIL JOINT.

1,161,472.

Specification of Letters Patent. Patented Nov. 23, 1915.

Application filed August 23, 1915. Serial No. 46,952.

To all whom it may concern:

Be it known that I, AMOS A. GROSE, a citizen of the United States, residing in Madison township, in the county of St. Joseph 5 and State of Indiana, have invented certain new and useful Improvements in Railway-Rail Joints, of which the following is a specification.

The invention relates to an improved rail 10 joint, wherein the meeting ends of the rails are of complementary formation to provide coöperating lips and recesses constructed to positively interlock and prevent endwise separation.

15 The essential element of connection of the improved joint resides in an integral tongue on each rail adapted to enter a corresponding recess of the other rail end, the tongue and wall of the recess having offset projections forming hook like elements which engage to prevent possibility of endwise separation.

20 The invention also contemplates the provision of a supplemental holding means to reinforce the hook connection, the supplemental reinforce permitting a slight relative lateral movement of the rail when under abnormal conditions, and re-alining the rear ends upon cessation of such abnormal strain.

25 The invention in the preferred form of details will be described in the following specification, reference being had particularly to the accompanying drawings, in which:

Figure 1 is a view in side elevation partly 30 in section of the improved joint; Fig. 2 is a plan of the same; Fig. 3 is a section on the line 3—3 of Fig. 1; Fig. 4 is a section on the line 4—4 of Fig. 3; Fig. 5 is an end view of one of the rails; Fig. 6 is a broken vertical 35 sectional view illustrating the supplemental fastening means; Fig. 7 is a broken face view of the web portion of the rail end to illustrate spring holding means; Fig. 8 is a side view of the nut illustrating the spring 40 engaging means.

In the accompanying drawing, illustrating the preferred detail of construction it will be noted that the respective meeting ends of the rails are of duplicate formation.

The following description therefore which 50 in general is limited to one rail end is to be taken as indicating the detail structure of each rail end.

Providing the improved rail connection the rail end has the tread 1 thereof arranged 55 to terminate on a line diagonal with respect to the length of the rail, such end surface 2 having the extreme edge portions thereof as 3 extending in opposite directions from and at right angles to the line of cut. This disposition is clearly illustrated in Fig. 2 of the drawings and provides for an interfit in the meeting ends of the rails throughout their tread portions.

The base flanges 4 are cut on similar diagonal lines and at one edge thereof the flange is extended beyond the diagonal line of cut in a longitudinally extending tongue 5 which is upstruck so as to lie in a plane slightly above the normal plane of the base 60 flange. The particular base flange at the opposite end of the diagonal line of cut is formed with a keeper 6 preferably by laterally projecting and return bending a length 65 of the base material, as more clearly illustrated in Fig. 5. The formation provides a keeper having an interior opening 7 of a size and so located as to accurately receive the tongue 5 of the opposing rail end. The web 8 of the rail is, a short distance rearwardly from the rail end deflected to one side to form what may be hereinafter termed 70 a pocket 9, such rail end in advance of the pocket being continued laterally in the vertical plane of the diagonal line of cut of the 75 tread and base flange, said laterally deflected portion 10 being hereinafter termed the web face. Immediately in advance of the pocket 9 and at a point approximately midway its height the web face is formed with an opening 11, this opening being by this disposition 80 practically in line with the plane of the main length of the web. Beyond the opening toward the free end of the web the face wall is of gradually increasing thickness as at 12, 85

the proportion of thickness being such that what may be termed the forward wall of the face 13 is in alinement with the surface 90 95

of the main length of the web. The thickened portion is in horizontal alinement with the opening 11, that is said web above and below the thickened portion is of normal 5 web thickness.

By this construction of the end of the web face there is provided approximately centrally of the height thereof an enlargement, and the end of such enlargement is formed 10 with a recess 14, so that beyond the web face proper the formation of the recess 14 provides a tongue 15, which tongue extends in the same direction as the web proper and slightly to one side thereof.

15 The terminal of the tongue 15 on the relatively inner side, that is the side next the web face, is formed to provide a hook 16, the recess 14 coinciding with the hook formation. The edge wall of the opening 11 forming the relatively rear boundary of same is also formed with a hook projection 17, that is the end of the pocket 9 terminates in such hook projection, as clearly shown in Fig. 3.

20 In associating the rail ends for interlocking it is designed to mate the respective tongues and openings by sufficient pressure and through such angular disposition of the rails as to cause the hooks of the tongues and 25 opening walls to interlock when the rail ends are brought into exact alining position, whereby possibility of endwise separation, to a very material extent is precluded. The coöperating tongues and openings are designed for extremely close fitting and it is 30 contemplated that machine force may be used if necessary in associating the rail ends to cause their interlock as described, under which force the respective coöperating hook 35 ends may yield sufficiently to permit them to be sprung to interlocking engagement.

As a supplemental means for securing the 40 connection to prevent possibility of endwise separation in the event the hook ends should become inoperative I form the respective web faces of the meeting ends of the rails adjacent the openings therein, each 45 with an opening 18 to receive a locking bolt 19. The bolt is headed at 20 and threaded 50 at the opposite end as at 21 to receive a nut 22, and a coil spring 23 is arranged between the nut and proximate surface of the web face. The spring is designed to be comparatively stiff, and the proximate surfaces of 55 the web face and nut 22 are each formed with an annular series of notches 24 in which pointed terminals 25 of the spring 23 are adapted to engage. This insures a locking 60 of the nut in place against possibility of casual displacement while at the same time permitting the desired and necessary function of the spring. It is obvious that by the supplemental connection described the joint

may yield laterally to an operative degree under abnormal strain, the spring serving to 65 restore normal conditions of the parts in relief of the strain.

What is claimed is:

1. A rail end having a web portion thereof deflected on a diagonal line to provide a 70 web face, said face being formed with a tongue and an opening arranged in horizontal alinement and in offset relation, the terminal of the tongue having a hook end.

2. A rail end having a web portion thereof deflected on a diagonal line to provide a 75 web face, said face being formed with a tongue and an opening arranged in horizontal alinement and in offset relation, the terminal of the tongue having a hook end, and 80 one wall of the opening having a hook projection to receive the hook tongue of the opposing rail end.

3. A rail end having a web portion thereof deflected on a diagonal line to provide a 85 web face, said face being formed with a tongue and an opening arranged in horizontal alinement and in offset relation, the terminal of the tongue having a hook end, and 90 one wall of the opening having a hook projection to receive the hook tongue of the opposing rail end, and supplemental fastening means engaging the rail faces of both rail ends.

4. A rail end having a web portion thereof deflected on a diagonal line to provide a 9 web face, said face being formed with a tongue and an opening arranged in horizontal alinement and in offset relation, the terminal of the tongue having a hook end, 100 and one wall of the opening having a hook projection to receive the hook tongue of the opposing rail end, and a locking bolt engaging the web faces of meeting rail ends, 105 said bolt being passed through the web faces intermediate the tongues and openings thereof.

5. A rail end having a web portion thereof deflected on a diagonal line to provide a 110 web face, said face being formed with a tongue and an opening arranged in horizontal alinement and in offset relation, the terminal of the tongue having a hook end, and 115 one wall of the opening having a hook projection to receive the hook tongue of the opposing rail end, and a locking bolt engaging the web faces of meeting rail ends, 120 said bolt being passed through the web faces intermediate the tongues and openings thereof, a nut engaging the bolt and a spring arranged intermediate the nut and web face.

6. A rail end having a web portion thereof deflected on a diagonal line to provide a 125 web face, said face being formed with a tongue and an opening arranged in horizontal alinement and in offset relation, the ter-

5 minal of the tongue having a hook end, and one wall of the opening having a hook projection to receive the hook tongue of the opposing rail end, and a locking bolt en- gaging the web faces of meeting rail ends, said bolt being passed through the web faces intermediate the tongues and openings thereof, a nut engaging the bolt and a spring arranged intermediate the nut and web face, said spring having adjustable in- terlocking coöperation with the nut.

In testimony whereof I affix my signature in presence of two witnesses.

AMOS A. GROSE.
